UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,278,828.

Specification of Letters Patent. Patented Sept. 17, 1918.

Application filed April 20, 1916. Serial No. 92,365.

To all whom it may concern:

Be it known that I, ARTHUR J. BAZELEY, a citizen of the United States, and a resident of Cleveland, Cuyahoga county, Ohio, 5 have invented new and useful Improvements in Car-Couplings, of which the following is a specification, reference being had to the accompanying drawings, in which—

Figure 1 is an elevation of a coupler embodying my invention; Fig. 2 is a bottom plan thereof; Fig. 3 is a section on lines III—III of Fig. 2 with the parts in locked position; Fig. 4 is a section similar to Fig. 3 but with the parts in knuckle thrown position; Fig. 5 is a section on lines V—V of Fig. 1 with the parts in locked position; Fig. 6 is a partial section similar to Fig. 5 but with the parts in knuckle thrown position; Figs. 7 and 8 are sections similar to 15 Figs. 5 and 6 respectively, but showing a modified form of operating lever.

My invention relates to car couplers of the vertical plane type, such as is shown in my Letters Patent No. 1,144,315, dated June 22, 25 1915, and provides novel mechanism for operating the coupler. My invention also relates to the various parts which I shall hereinafter describe and claim.

Referring to the drawings, A indicates a 30 coupler-head, B the knuckle, C the lock, D the knuckle-thrower, E the operating lever and F the lifting link. The operating lever E is of the bell-crank type, comprising the arms 2 and 3, pivoted at their juncture in the 35 sides of a stirrup-shaped piece 4, by the pin 5. The stirrup-shaped piece depends beneath the coupler head and its bottom stiffens the sides and keeps them the proper distance apart, so that they may not become accidentally bent in upon the lever E so as to bind it. The upper end of the lever E is formed in any convenient way, such as being 40 forked, as shown, to provide a convenient connection for an actuating rod, and is preferably located forward of the buffering horn of the coupler-head, so as to be protected from injury by the buffer plate on the car. The lower arm 3 of the lever E is enlarged at its lower end, as is shown in Figs. 2 and 3, 45 and the upper surface 6 of the enlarged end is beveled, so as to slope slightly downward to the rear of the coupler-head and also toward the guard-arm side. The lifting link F is provided with trunnions 7, which operate in vertical slots 8 of the lock-hole pocket,

and has on its upper extension 9 a laterally-extending arm 9^a, which seats in the slotted opening 10 in the leg 11 of the lock C.

The operation of the coupler is as follows:

When the parts are in locked position, as 60 is shown in Figs. 3 and 5, the upper end 9 of the lifting link F underlies the anti-creep projection 12 on the under side of the coupler-head, and as the operating lever is actuated and the lower end of its arm 3 rises, the 65 highest point 13 on its upper surface 6 strikes the cam surface 14 on the under side of the lifting link F at a point forward of the trunnions 7 on the link, and also forward of the center of gravity of the link. The 70 contact between the cam surface 6 on the operating lever with the cam surface on the bottom of the link tends to throw the arm 9^a of the lifter rearwardly, as is permitted by the inclined slot 10 in the lock-leg 11, and 75 by the same operation the upper end 9 of the link moves out from beneath the anti-creep ledge 12. As the lever E continues to lift, its point of contact with the link F always remains forward of the point of contact between the link and the lock-leg 11, so that the link at all times tends to throw the leg of the lock rearwardly.

When the lock C has been lifted until the 80 projection 15 on the forward face of its head strikes the fulcrum 16 in the coupler-head, further vertical movement is impossible, and the leg of the lock must necessarily swing rearwardly against the knuckle-thrower D. It will thus be seen that the 85 rearward thrust of the lifting link upon the lock-leg is assisted by the fulcruming of the lock upon the coupler-head, and that these two forces will result in a powerful rearward or knuckle-throwing pressure upon the 90 knuckle-thrower D.

During the vertical movements of the lifter the slots 8 serve merely as guides for the trunnions 7 of the link. When the link has reached the top of its travel and the 100 knuckle has been thrust open, there is still clearance between the top of the slots and the trunnions 7, as is shown in Fig. 4. It will therefore be seen that the link and the lock form a toggle joint, and the break of 105 the joint to the rear is initially obtained by lifting the link at a point forward of its center of gravity, which causes its upper end to tip rearwardly. During knuckle-throwing the lock fulcrum becomes the upper or sta- 110

tionary end of the toggle, while the operating lever forces upward the lower end of the lifter link, so that the connection between the link and the lock-leg is the elbow of the toggle, and is forced to move rearwardly. After the parts are lockset or the knuckle is thrown, the operating lever is free to return to its normal position against the side of the coupler-head, where it is as described above, 10 protected from accidental breakage by the horn of the coupler.

If necessary, the lifting link may be secured to the lock by passing a cotter pin through the hole in the end of the arm 9^a, 15 so that the link and the lock will not become separated when the knuckle is removed from the coupler. When the parts are in the coupler, however, the walls of the opening for the leg of the lock and the guiding slots 20 8 for the trunnions 7 keep the arm 9^a in position in the slotted opening 10, and thereby hold the link and lock-leg in engagement.

In Figs. 7 and 8 I have shown a modified 25 form of my device, in which a rider 17 is pivoted to the end of the operating lever E'. The upper surface of the rider is flat and, by its pivotal engagement with the lever E', always maintains a flat bearing 30 upon the bottom of the lifter link F'. The rider 17 is counterweighted, so that it will always return to upright position when not in contact with the lifter link.

The terms and expressions which I have 35 employed are used as terms of description and not of limitation, and I have no intention, in the use of such terms and expressions, of excluding any mechanical equivalents of the features shown and described, 40 or portions thereof, but recognize that various structural modifications are possible within the scope of the invention claimed.

What I claim is:

1. In a car-coupler, a lock having a down- 45 wardly-extending leg and having also a fulcrum bearing on its forward portion, and a lifting mechanism for said lock comprising a transversely extending lever pivoted to the coupler-head and a link adapted to 50 be engaged by said lever and having a pivotal engagement with the lock-leg, said link in its initial position being adapted to be rotated and then to lift the lock per-

pendicularly and at the same time move it rearwardly, the said link and lock comprising a toggle joint, which, on engagement of the fulcrum on the lock with the coupler-head, breaks positively to the rear for lock-setting and knuckle-throwing. 55

2. In a car-coupler, a lock having a depending leg, and a lifting link operating in a depending portion of the coupler-head and engaging the lock-leg, said link having trunnions operating in vertically-extending guides in said depending portion of the 60 coupler-head, said link, upon actuation by an operating lever being adapted to be lifted vertically and to be rotated rearwardly about said trunnions, to throw the leg of the lock rearwardly for locksetting and 65 knuckle-throwing.

3. In a car-coupler, a lock having a depending leg, the leg of the lock having a slot in its lower end, a lifting link having trunnions at its rear side and a forward 75 extension seating in the opening in the lock-leg and a forward portion adapted to be engaged by an operating lever, whereby on actuation by the lever the lock-lifter will tilt rearwardly about said trunnions and 80 will move vertically, thereby causing the leg of the lock to move rearwardly.

4. In a car-coupler, a lock having a depending leg, the leg of the lock having a slot in its lower end, a lifting link pivoted in 85 said slot and normally depending from said lock-leg, and an operating lever normally out of contact with the link adapted to be rotated into engagement with the under-side 90 of the link to lift it and tilt it rearwardly whereby the link will lift and carry the leg of the lock to the rear.

5. In a car-coupler, a lock having a depending leg, a lifting link operating in a depending portion of the coupler head and 95 engaging the lock leg, a lever operating transversely of the coupler head, having a cam surface thereon, a cam surface on the lower end of the link, the cam surface on the lever being adapted on actuation of the 100 lever to engage the cam surface on the link, and lift it and tilt its upper end to the rear, thereby forcing the leg of the lock rearwardly for lock setting and knuckle throwing.

ARTHUR J. BAZELEY.
